METHOD OF ORNAMENTATION

Filed April 11, 1922

UNITED STATES PATENT OFFICE.

THEOPHIL PFISTER, OF NEW YORK, N. Y., ASSIGNOR TO TAPESTRELLE CORPORATION, OF NEW YORK, N. Y., A CORPORATION OF NEW YORK.

METHOD OF ORNAMENTATION.

Application filed April 11, 1922. Serial No. 551,476.

To all whom it may concern:

Be it known that I, THEOPHIL PFISTER, a citizen of the United States, residing at New York, in the county of New York and State of New York, have invented certain new and useful Improvements in Methods of Ornamentation, of which the following is a specification.

The invention has for an object to effect improvements in methods of ornamentation of objects, such as shades, panels, screens, and the like. It is an important aim of the invention to effect economy in the formation of designs for various objects, and an important aim is to enable the development of a series of designs with a common scheme or motif without necessitating the printing of the various designs as separate operations or from separate plates. It is an important aim also to enable the provision of a design in a given motif for articles of various forms, without the printing or drawing of a special outline adapted to fit the article contemplated, and to even obviate the necessity for preparing a special design to fit the shape of a given article.

Additional objects, advantages and features of invention may be understood from the disclosures hereinafter, including a description, in connection with drawings, wherein,

Figure 1 is a view of a piece of goods having a design blocked out thereon to fit a given article,

Fig. 2 is a view of an article having a design of a different size and shape taken from the same piece of goods,

Fig. 3 is a similar view of a still further article, having an appropriate design of a different size and shape from the other mentioned and taken from the same piece of goods.

Fig. 4 is a sectional view of an ornamental panel constructed in accordance with my invention, the thickness of the parts being greatly exaggerated.

My invention aims to enable the production of ornamental lamp shades with translucent designs which also show as surface ornamentations by reflected light. It has

been a practice heretofore, to use designs printed in colors or otherwise, upon a suitable medium which may be translucent, or may be made translucent readily, the medium being either of sufficient body itself, or having a backing of a suitable body to enable its proper use in the way contemplated. Ordinarily, special pieces of patterns having designs fitted to the shape of the finished article to be made are provided.

By my method, however, I print, or secure a fabric printed with, a multifarious design utilizing practically the full surface area of the fabric, which may be either paper, or woven goods, the design being of a character to permit various parts to be blocked out so as to form a large pattern, or a small pattern, or the parts retained in such location as to fit the design to various outlines, as, square, triangular, frusto-conical, circular, et cetera.

In one method of the practice of my invention, I procure a fabric such as cretonne, for instance, although various other kinds of goods may be employed, in which the design is either printed or woven; this goods is cemented upon a foundation, which may be either semi or completely transparent, and may comprise paper, parchment, or glass, as indicated at 11 in Fig. 4, ordinarily, the material having the design thereon being adjusted upon the support to lie within the pattern of the support, or boundary of the finished article, as will become more clearly apparent hereinafter. These materials may be cemented together by means of varnish, or otherwise, as found desirable.

When the multifarious design is thus secured, it will be found that there are elements within the proposed boundaries of the finished article which are not properly inclusive, under the rules of composition, with the design which it is proposed to retain as the salient ornamentation of the article. Therefore, I take an opaque pigment and paint upon the surface of the fabric following close against the outlines of the proposed unitary design which is to be retained, after the manner indicated by the diagonal hatching of Figures 1, 2, and 3. If the de-

sign is for a large lamp shade, for instance, a large number of elements of the complete printed fabric may be retained as those of unitary design, as shown in Fig. 1, certain elements of design as indicated at 12, 13, and 14, being blocked out entirely, although these parts upon a similar piece of goods may be utilized for a separate panel of like size and shape, or at a different part of the 10 same piece of goods on the particular shade or other article beyond the boundaries illustrated in Fig. 1. When this blocking out is completed, the entire surface including the blocked out portion and that part of the 15 fabric which is not covered by the opaque pigment is covered with a cementitious material or adhesive 16, which may be a suitable varnish if desired, and upon this there is sprinkled fine globular glass or blank 20 beads 17, which impart to the finished article a velvety appearing surface and rich texture. The surplus being shaken off, the adhering portions may be rolled to give a 25 good flat surface to the finished article, if desired.

By thus using in one portion of a design, parts which are blocked out in another part, a considerable variety may be secured upon one article, especially when a screen-like effect is required, with the use of a single pattern design. In a like manner, the same design may be utilized to provide various ornamented parts with different designs, of the same motif, as shown in Figs. 2 and 3, and these would harmonize properly with a design such as that shown in Fig. 1, so that a complete set, including such articles as lamp shades, candle shades, et cetera, may be formed in the same motif with various designs, from a single pattern. It will be noted that on the pattern at 10, there is shown a bird in a different position from that shown in full lines in Figure 1, the detail at 10 being blocked out where it protrudes upon the design, while at 13 a bird in a further different position is shown, blocked out, and at the location 15 the foliage is blocked out, any or all of which might be used in other panels formed from 40 the same kind of pattern, or the same pattern, this design being suitably extended, as will be understood. The article shown in Fig. 2 has a design formed from a part of the full design utilized in Fig. 1, and taken from the lower left hand corner of 45 Fig. 1. The dotted line 18 of Fig. 1 represents the manner in which the design of Fig. 3 is effected.

The opaque pigment utilized for the blocking out is preferably one which would have a value in reflecting light, as, a blue, a green, or other color which will harmonize with the design outlined by the opaque material. However, in some articles and some 50 designs, it may be found preferable to use

a white or black pigment, as the opaque element.

In case the printed pattern utilized is not sufficiently strong in color, this may be strengthened by colored paints which are 55 not opaque, but of sufficient density to give the necessary tone value to the design when illuminated by transmitted light.

In making the device, the foundation is 60 cut out to the desired shape for the finished article, and the pattern goods adjusted thereon, before the blocking out is done, or, the pattern goods may be cemented upon the foundation material and the blocking out done on a large scale, after which the 65 necessary parts may be cut out and fitted in the articles in which ornamental illuminated panels are desired. By utilizing the glass covering, the panel will also have an 70 ornamental value under light reflected therefrom. The mounting of the panels may be accomplished in any manner 75 familiar in the mounting of panels formed by other methods with a similar use.

What is claimed:—

1. A pattern for forming ornamental panels of various designs consisting of a sheet having depicted thereon representations of various details in a given motif and in a relation to permit blocking out of parts 80 to form different unitary designs alternatively with the remaining parts, the details being of a character to be repeated, whereby parts blocked out at one point may be retained at another part, whereby the same area of the pattern material may be utilized to produce different designs of like 85 dimensions.

2. The method of forming ornamental designs of various sizes and shapes consisting in utilizing a pattern material having a multifarious configuration thereon in a relation to permit blocking out of parts alternatively, adjusting a suitable part of the pattern to the outline of the object contemplated, and blocking out the parts without such outline and those parts intruding 90 which are not unitary with the selected part and the outline.

3. The method of forming a set of ornamented objects of various kinds in a given motif consisting in utilizing a pattern material having a multifarious configuration thereon in a given motif and in a relation to permit blocking out of parts alternatively to form from different parts separate unitary designs, adjusting appropriate parts of the pattern to the outlines of the articles to be ornamented according to their 95 size and shape, blocking out the parts intruding within the outlines which are not unitary with the design selected and with the outline with which they are associated.

4. The method of forming an ornamental panel piece to be viewed by light trans-

mitted therethrough consisting in utilizing a fabric having a multifarious pattern, selecting a part appropriate to the size and shape of the panel, forming a base of the required shape, cementing the fabric thereon with the selected pattern in proper relation to the outline of the panel, blocking out intruding parts of the pattern not unitary with that selected with an opaque and applying a finishing surface to the panel piece.

In testimony whereof I have affixed my signature.

THEOPHIL PFISTER.
